CLAIM

The ornamental design for a clock face, as shown and described.

DESCRIPTION

FIG. 1 is a top front perspective view of a clock face showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines shown in the drawings illustrate a boundary of the clock face that forms no part of the claimed design.
